CLAIM

The ornamental design for a scrub brush, as shown and described.

DESCRIPTION

FIG. 1 is a rear perspective view of a scrub brush in accordance with the present disclosure;

FIG. 2 is a front view of a scrub brush in accordance with the present disclosure;

FIG. 3 is a rear view of a scrub brush in accordance with the present disclosure;

FIG. 4 is a side view of a scrub brush in accordance with the present disclosure;

FIG. 5 is a top view of a scrub brush in accordance with the present disclosure; and,

FIG. 6 is a bottom view of a scrub brush in accordance with the present disclosure.

The evenly spaced broken lines and unshaded areas within the evenly spaced broken lines depict environmental structure that forms no part of the claimed design. The dot-dash broken lines immediately adjacent to the shaded areas depict the boundaries of the claim and form no part of the claimed design.

1 Claim, 5 Drawing Sheets

Related U.S. Application Data

a continuation of application No. 29/555,926, filed on Feb. 25, 2016, now Pat. No. Des. 845,001.
